CLAIM

I claim the ornamental designs for a lighting fixture, as shown and described.

DESCRIPTION

FIG. 1 is a perspective view of a lighting fixture showing the new design. Excluding the hanging loops, this fixture has mirror image symmetry (one hundred eighty degree overall rotational symmetry and mirror image symmetry along a first vertical imaginary plane and also mirror image symmetry along a second vertical imaginary plane, with the first and second vertical imaginary planes being orthogonal to each other). The stems, lamp bases, and shades each have a circular horizontal cross-section, and the rods composing the frame each have a square cross-section.

FIG. 2 is a front elevation view thereof.

FIG. 3 is a side elevation view thereof; and,

FIG. 4 is a partial top plan view thereof with a portion of the disclaimed subject matter omitted.

The dashed lines on the drawing depict portions of the lighting fixture that form no part of the claimed design.
